ROTARY COMPRESSOR

Paul E. Good, Riverton, N. J.

Application July 26, 1937, Serial No. 155,810

18 Claims. (Cl. 230—150)

This invention relates to rotary compressors for pumps, and more particularly to devices of this character such as illustrated in my prior Patent No. 1,989,552, granted January 29, 1935, for "Rotary compressor".

The type of compressor illustrated in said patent comprises a rotor having a circumferential series of spirally directed grooves, a suitable casing surrounding said rotor and carrying and rotatably supporting a plurality of pistons having lobes to engage said grooves and block the same from end to end as the rotor is rotated, and means in said casing defining intake and exhaust channels.

This structure, while admirably adapted to many uses in the compressor field, presents difficulties in construction, and more particularly in the production of housings and mountings for the rotatable piston elements and in the provision of the necessary intake and exhaust grooves.

An important object of the present invention is the provision of a structure such that the mounting and housing of the piston or barrier elements is simplified and the extensive and complicated coring necessary in the production of the exhaust and intake channels is reduced to a minimum and the general structure of the several elements so designed that the proper assembly of the same may be assured by relatively simple machining processes.

Another object of the invention is to provide a construction such that the exhaust and intake channels may be arcuately divided, thus materially simplifying the patterning and machining of the structure.

Another object of the invention is the production of a structure which lends itself readily to considerable modification such as the amplification or reduction of the number of barrier elements employed, to modification to enable fluids to be simultaneously pumped to several different points by the same compressor structure, and to the inclusion in the compressor structure of multi-stage compression.

These and other objects I attain by the structure shown in the drawings wherein:

Fig. 1 is a vertical transaxial view of a compressor constructed in accordance with my invention;

Fig. 2 is a section on line 2—2 of Fig. 1;

Figs. 3 and 4 are perspective views of the outer casing sections or barrier mountings;

Fig. 5 is a perspective view showing the rotor and cylinder combined;

Fig. 6 is a perspective view of the rotor;

Fig. 7 is a diagrammatic view showing the gearing employed in driving the barriers when such is desired;

Fig. 8 is a perspective view of the assembled structure;

Fig. 9 is a view partially in diametral section showing a multi-stage compressor constructed in accordance with my invention;

Fig. 10 is a section on line 10—10 of Fig. 9; 10

Figs. 11, 12 and 13 are views showing modified arrangements of the compressor casing structure;

Figs. 14, 15 and 16 are semi-diagrammatic views showing the barrier arrangements of the structures illustrated in Figs. 11 to 13 respectively; 15

Fig. 17 is a section on line 17—17 of Fig. 12;

Fig. 18 is a modification of the arrangement shown in Fig. 17; and

Fig. 19 is a fragmentary sectional view similar 20 to that in Fig. 10 and illustrating a modified method of obtaining reduced groove capacity.

Referring now to the drawings, and more particularly to Figures 1 to 8 thereof, wherein I have illustrated a compressor utilizing two grooves 25

in the rotor and two symmetrically arranged barrier elements for coaction with said grooves, and a casing structure wherein the intake and exhaust of the grooves have common ports, the numeral 10 generally designates a rotor comprising a shaft 11 and a rotor body 12 secured thereto, such rotor body having a truly cylindrical periphery provided with a series of spirally extending grooves 13 which are symmetrically arranged thereabout so that the rotor body may remain in dynamic balance. An end of the rotor shaft is, in the present instance, illustrated as provided with a gear 14, the purpose of which will hereinafter appear. Surrounding the rotor body is a cylinder 15 the inner surface of which is 40

truly cylindrical and has a sliding fit with the periphery of the rotor. This cylinder is formed with slots 16 through which the lobes 17 of the rotatable piston elements or barriers 18 are adapted to extend for engagement in the grooves 45

13. These slots, as originally formed, are somewhat wider and longer than the width and trajectory of the lobes, and have their margins kerfed as at 19 to provide an anchorage for a cast-in bearing-metal finishing piece 20 which, 50

in the final process is accurately machined to accommodate the pistons.

The exterior face of the cylinder is provided with ribbing 21 defining the slots 16 and with circumferential ribbings 22, 22a and 22b defining 55

intake and exhaust channels 23 and 24 between adjacent ribbings 21. The exteriors of these ribbings are circumferentially smooth and are arranged upon a single truly cylindrical surface so that they may be conveniently finished by a simple machining operation. The ribs are formed with dowel notches 25 for the reception of inserted dowels 26 carried by the coacting casing sections now to be described.

10 The casing is formed in a plurality of sections, S, one for each barrier element 18 which is to be employed in the compressor, such sections each comprising an outer wall 27 having inwardly extending marginal ribbings 28 for engagement with the ribbings 22, 22b of the cylinder, a central rib 29 for coaction with the medial rib 22a of the cylinder, and transverse ribbing 30 for coaction with the ribbing 21. In the assembled relation of the casing sections, the ribbings 22, 22a, 22b and 28 and 29 combine to produce annular channels. The sections of these channels which, in the form at present under discussion, lie at opposite sides of the ribbings 21 and 30, are placed in communication with one another by transfer ports 31, 31a formed by abbreviation of the ribbings 30 of the casing elements and the connection of these ribbings by a web 32.

Since the outer surface of the ribbing of the cylinder 15 presents a truly cylindrical surface, it is simply necessary, in order that a proper clamping fit between the casing sections and cylinder be provided, that the sections forming the casing be bolted together as by bolts 33 extending through openings 34, and accurately bored to the desired diameter.

By utilizing this construction, the formation of cores necessary to the production of intake and exhaust ports 35 and 36, the intake and exhaust channels, and the housing for the barrier elements is greatly simplified. Furthermore, as will be hereinafter more fully brought out, the construction just recited is particularly advantageous in that by a simple modification of the core structure necessary in the formation of the casing elements, the ports 31 may be blocked, thus enabling segregation of the intake or exhaust, or both, for any section or group of sections in the compressor structure. This variation of the structure will be discussed more fully hereinafter in connection with Figures 12, 15, 17 and 18. Additionally, the separate formation of the cylinder permits ready variation of the pattern to control the size of the ports where fixed ports are to be employed, and the cylinder wall proper is always readily accessible for machining to form valve seats where such are to be employed as described in my prior patent hereinbefore mentioned.

In order that the pistons 18 may be conveniently mounted in the casing sections, I form in each section which is to mount a piston a straight bore 37 considerably larger than the shaft 38 mounting the piston, as more clearly shown in Fig. 1. This bore intersects the ribbing 30 of the casing section and partially interrupts the inner periphery of the same. Within the bore, I arrange bushings 39 and 40, these bushings, upon insertion, projecting into the interior of the casing section and interrupting the inner periphery of the same prior to the machining operation by which they are given the same cylindrical contour as the casing sections and the periphery of the cylinder. Dowels 41, or some similar expedient, may be employed for locating the bushings, and the bushing 40 is utilized as a

support for a sealing packing 42 and the bearing 43 for the shaft. The bushing 39 is, as illustrated, utilized solely as a support for a sealing packing 42a, the corresponding end of the shaft 38 being supported through a bearing 44 mounted in an end closure bushing 45 having a removable cap plug 46 through which access may be had to the end of the shaft and to the lock nuts 47 securing the bearing 44 in position.

The opposite end of the bore 37 is closed by a simple closure plate 48. The bore 37, adjacent the closure plate 48, is interrupted by the perpendicularly related bore 49 which is similarly closed, and the closure plates 48 and 50 when removed afford access to the driving connection between the shafts 38 and perpendicularly related shafts 51, the outer ends of which are connected with the gear 14 of the rotor shaft through gearing 52, as suggested in Fig. 7. This gearing, as more clearly shown in Figure 2, may be conveniently housed by an oil-tight cover plate 53 secured to the housing sections. The piston housings are preferably provided at the outer wall of the associated casing section with inspection openings 53a closed by plates 53b; these openings will permit the condition of the piston to be examined at any time without the necessity for dismantling the compressor.

As a means for securing proper centering of the rotor and cylinder and holding the casing against axial displacement, and as a means for conveniently supporting the rotor, end plates 54 are utilized, these plates being secured to the cylinder wall and slightly overlapping the casing sections as indicated at 55. The plates have additionally an inwardly extending annular boss 56 interiorly fitting the cylinder and are formed centrally with openings 57 for the reception of bearing mounts 58 mounting bearings 59 for the shaft 11 of the rotor. Inwardly of the bearing plates the bosses are constructed to mount oppositely facing sealing packings 60 and 61 which serve respectively to exclude lubricants necessary to the bearings 59 from the interior of the casing and to seal against the outward passage of air about the rotor shaft.

The construction just described, obviously, lends itself readily to considerable modification without departing from the principles utilized therein. In Figures 9 and 10 I have illustrated this construction as applied to a multi-stage compressor and it will be noted that, other than the necessary changes to effect a second compression, i. e., the use of secondary grooves 62 of less capacity than the grooves 63 of the initial stage and the use of properly proportioned barriers 64, 65 for co-action with these grooves, the sole modification necessary is the omission of one of the marginal ribs of the casing structure so that the exhaust channel of the first stage and the intake channel of the second stage become a common channel 66. Insofar as the machining operations and assembly are concerned, the structure remains identical with the structure originally described.

In the form at present illustrated, in addition to the supply and exhaust ports 67, 68 for intake and exhaust channels 23, 24, a take-off port 69 may be provided for the channel 66 through which a portion of the first stage of compression 70 may be removed as desired. It will, of course, be understood that, under these circumstances, the intake end of the compressor will have a capacity exceeding that of the exhaust end by the amount of fluid which it is desired to remove at 75

port 69. In the simple form of this structure the relative capacity of these sections will be such that the fluid as compressed in the first or intake section is just sufficient to supply the grooves of the secondary exhaust section. It will be also noted from these figures that barriers or pistons having a different number of lobes may be employed, the illustration showing the intake section as employing a four-lobe barrier and the 10 exhaust section employing a five-lobe barrier. Reduced capacity of the discharge may also be readily obtained by internally increasing the thickness of the cylinder wall and correspondingly reducing the rotor diameter as suggested in 15 Figure 19.

A characteristic end elevation of the structures of Figs. 1 to 10 is shown in Fig. 11, and in Fig. 14 I have diagrammatically illustrated the barrier piston arrangement employed therein. 20 In Fig. 12 I have illustrated the use of a greater number of casing sections, each supporting a barrier, four being illustrated in the present instance, as indicated in the diagrammatic showing of Fig. 15. In this figure I have, likewise, illustrated an arrangement whereby fluids may be simultaneously pumped to different destinations in desired quantities. This is accomplished, as hereinbefore briefly noted, by blocking the port 31 or 31a, or both, in certain of the casing sections. In Fig. 17 a sectional view of the casing section is given, taken immediately adjacent the barrier casing. It will be noted that no by-pass ports 31 or 31a are employed, and since the arrangement illustrated in Figure 17 is common to 30 both barriers on the diameter A—A the structure illustrated in reality comprises two separate compressors arranged on opposite sides of the diameter A—A, such compressors having a common rotor. Each section A or B may then be provided with an individual intake 70 and exhaust 71. By suitably varying the number of sections, the desired proportions pumped by either compressor section may be determined. If desired, a multiplicity of minor sections such as 40 45 A and B may be provided and these given a common intake by simply utilizing the intake by-pass 31 and blanking off the exhaust by-passes as suggested in Fig. 18.

In some instances, it may be desirable to employ an arrangement such as shown in Fig. 13 which diagrammatically illustrates a compressor structure which could be readily employed as a supercharger for an engine the base or underlying support of which would not permit the use 50 55 of a casing section at the lower portion of the compressor body. Under these circumstances, barriers may be grouped as suggested in Figure 16 and a section 72 employed which simply blanks off the space provided for an additional section. Obviously, this blanking section 72 might be located at any point desired about the circumference, replacing any of the sections 73.

Since the construction illustrated and described is capable of many variations other than 60 65 those specifically illustrated, I do not wish to be understood as limiting myself thereto except as hereinafter claimed.

I claim:

1. In a rotary pump of the type described, a 70 rotor having an annular series of spirally extending grooves, an annulus surrounding the rotor and having external ribs defining a circumferential channel and a radially directed axially disposed slot, the outer faces of said ribs being disposed upon a common diameter, a casing element

closing the channel and combining with that portion of the ribbing defining the slot to produce a piston housing, a rotary piston in and carried by said housing element having lobes meshing in said rotor grooves and successively blocking 5 said grooves from end to end as the rotor is rotated, and means to supply fluid to said grooves, the inner wall of the channel having an exhaust port adjacent one face of the ribbing defining the slot and the channel having a delivery port. 10

2. In a rotary pump of the type described, a rotor having an annular series of spirally extending grooves, an annulus surrounding the rotor and having external ribs defining a plurality of circumferentially spaced radially directed axially disposed slots and between said slots circumferentially extending channels, the outer faces of said ribs being disposed upon a common diameter, casing elements closing the channels and combining with those portions of the ribbing defining the slots to produce piston housings, a rotary piston in each housing and carried by the associated casing element, said pistons having lobes meshing in said rotor grooves and successively blocking said grooves from end to end as 20 the rotor is rotated, and means to supply fluid to said grooves, the inner wall of each channel having an exhaust port adjacent one face of the ribbing defining the slot and means to deliver fluid 25 from the channels. 30

3. In a rotary pump of the type described, a rotor having an annular series of spirally extending grooves, an annulus surrounding the rotor and having external ribs defining a plurality of circumferentially spaced radially directed axially disposed slots and between said slots circumferentially extending channels, the outer faces of said ribs being disposed upon a common diameter, casing elements closing the channels and combining with those portions of the ribbing defining the slots to produce piston housings, a rotary piston in each housing and carried by the associated casing element, said pistons having lobes meshing in said rotor grooves and successively blocking said grooves from end to end as 40 the rotor is rotated, and means to supply fluid to said grooves, the inner wall of each channel having an exhaust port adjacent one face of the ribbing defining the slot, ports in said casing elements placing the channels in communication 45 with one another and a delivery port in one of said casing elements. 50

4. In a pump of the type described, a rotor having a circumferential series of spirally disposed grooves, an externally cylindrical cylinder 55 surrounding and fitting the rotor, complementary segmental casing sections clamped about said cylinder and rotatable pistons carried by at least some of said casing sections and having lobes to engage in said grooves and successively block 60 said grooves from end to end as the rotor is rotated, said cylinder having axially-directed radial slots for the passage of the lobes of said pistons, and ribbing on said casing sections including 65 axial ribbing defining the slots of the cylinder and providing a housing for the associated piston and circumferential ribbing defining an exhaust channel, said ribbings having their circumferential faces disposed upon a common diameter and 70 having operative sealing engagement with said cylinder, and said cylinder having an exhaust port adjacent each of said slots. 75

5. In a pump of the type described, a rotor having a circumferential series of spirally dis-

posed grooves, an externally cylindrical cylinder surrounding and fitting the rotor, complementary segmental casing sections clamped about said cylinder and rotatable pistons carried by at least 5 some of said casing sections and having lobes to engage in said grooves and successively block said grooves from end to end as the rotor is rotated, said cylinder having axially-directed radial slots for the passage of the lobes of said pistons, and 10 ribbing on said cylinder including axial ribbing defining the slots and in part providing a housing for the associated piston and circumferential ribbing defining an exhaust channel, said ribbings having their circumferential faces disposed 15 on a common diameter and having operative sealing engagement with said casing sections and said cylinder having an exhaust adjacent each slot.

6. In a pump of the type described, a rotor having a circumferential series of spirally disposed 20 grooves, an externally cylindrical cylinder surrounding and fitting the rotor, complementary segmental casing sections clamped about said cylinder and rotatable pistons carried by at least 25 some of said casing sections and having lobes to engage in said grooves and successively block said grooves from end to end as the rotor is rotated, said cylinder having axially-directed radial slots for the passage of the lobes of said pistons, and 30 complementary ribbing on said cylinder and casing sections comprising axial ribbing defining the slots and providing a housing for the associated piston and circumferential ribbing defining an exhaust channel, said ribbings having their circumferential faces disposed on a common diameter and having operative sealing engagement 35 with one another.

7. In a rotary pump of the type described, a rotor having an annular series of spirally extending 40 grooves, an annulus surrounding the rotor and having external ribs defining a plurality of circumferentially spaced radially directed axially disposed slots and between said slots circumferentially extending channels, the outer 45 faces of said ribs being disposed upon a common diameter, casing elements closing the channels and combining with those portions of the ribbing defining the slots to produce piston housings, a rotary piston in each housing and carried by the 50 associated casing element, said pistons having lobes meshing in said rotor grooves and successively blocking said grooves from end to end as the rotor is rotated, and means to supply fluid to said grooves, the inner wall of each channel having an exhaust port adjacent one face of the ribbing defining the slot, ports in said casing elements placing the channels in communication with, one another, a delivery port in one of said casing elements, and ports in certain of said casing 55 sections placing the channels at opposite sides of the associated rotary piston in communication with one another, the remaining casing elements constituting dams defining the ends of the channels.

8. In a pump of the type described, a rotor having a circumferential series of spirally disposed 60 grooves, an externally cylindrical cylinder surrounding and fitting the rotor, complementary segmental casing sections clamped about said cylinder and rotatable pistons carried by at least 65 some of said casing sections and having lobes to engage in said grooves and successively block said grooves from end to end as the rotor is rotated, said cylinder having axially-directed 70 radial slots for the passage of the lobes of said

pistons, ribbing on said cylinder including axial ribbing defining the slots and in part providing a housing for the associated piston and circumferential ribbing defining an exhaust channel, said ribbings having their circumferential faces disposed on a common diameter and having operative sealing engagement with said casing sections and said cylinder having an exhaust port adjacent each slot, and ports in certain of said casing sections placing the channels at opposite 10 sides of the associated rotary piston in communication with one another, the remaining casing elements constituting dams defining the ends of the channels. 5

9. The structure of claim 2 wherein the casing 15 elements have complementary ribbing sealingly engaging the ribbing of the annulus.

10. A device as claimed in claim 1 wherein the portions of the channel at opposite sides of the rotary pistons are in communication with one 20 another. 20

11. A device as claimed in claim 1 wherein the portions of the channel at opposite sides of certain of the rotary pistons are in communication with one another and are segregated from the 25 remaining portions of the channel. 25

12. In a rotary pump of the type described, a rotor having a pair of annular series of spirally extending grooves, the grooves of one series having lesser capacity than the grooves of the other 30 series, an annulus surrounding the rotor and having external ribbing defining two circumferential channels and radially directed axially disposed slots in alignment with each of said groove series, the outer faces of said ribs being disposed upon a common diameter, casing elements closing the channels and combining with those portions of the ribbing defining the slots to produce piston housings, rotary pistons in and carried by said housings having lobes meshing in the grooves 35 of each series and successively blocking said grooves from end to end as the rotor is rotated, means to supply fluid to said grooves, the inner wall of one channel having exhaust ports for cooperation with one series of grooves and intake ports for 40 cooperation with the other series of grooves, the inner wall of the other channel having exhaust ports for cooperation with the last-named series of grooves. 45

13. In a rotary pump of the type described, a 50 rotor having a pair of annular series of spirally extending grooves, the grooves of one series having lesser capacity than the grooves of the other series, an annulus surrounding the rotor and having external ribbing defining two circumferential 55 channels and radially directed axially disposed slots in alignment with each of said groove series, the outer faces of said ribs being disposed upon a common diameter, casing elements closing the channels and combining with those portions of the ribbing defining the slots to produce piston housings, rotary pistons in and carried by said housings having lobes meshing in the grooves of each series and successively blocking said

grooves from end to end as the rotor is rotated, 60 means to supply fluid to said grooves, the inner wall of one channel having exhaust ports for cooperation with one series of grooves and intake ports for cooperation with the other series of grooves, the inner wall of the other channel having exhaust ports for cooperation with the last-named series of grooves, that portion of the rotor having the groove series of lesser capacity being of reduced diameter, the inner wall of the cylinder being thickened to an internal diameter cor- 70 75

responding to that of the reduced portion of the rotor.

14. A device as claimed in claim 12 wherein the casing sections have ribbing complementary to the ribbing of the cylinder and in sealing engagement therewith.

15. A device as claimed in claim 3 wherein the portions of each channel at opposite sides of certain of the rotary pistons are in communication with one another and are segregated from the remaining portions of the channels.

16. A device as claimed in claim 4 wherein the

portions of each channel at opposite sides of certain of the rotary pistons are in communication with one another and are segregated from the remaining portions of the channel.

17. A device as claimed in claim 3 wherein the channels at opposite sides of the rotary pistons are in communication with one another.

18. A device as claimed in claim 4 wherein the channels at opposite sides of the rotary pistons are in communication with one another.

10

PAUL E. GOOD.
